COMBINATION LOCK

Joseph Spadafora, Medford, Mass., assignor of
fifty per cent to Conrad Zammitti, Boston,
Mass.

Application January 8, 1936, Serial No. 58,172

3 Claims. (Cl. 70—303)

This invention relates to a combination lock, the general object of the invention being to provide a plurality of rotatably arranged rings having slots therein with a bolt controlling member movable into the slots when the rings have been moved to align the slots, a knob for rotating the rings, adjustable means for regulating the rotary movement of the rings by the knob and pins for controlling the amount of rotation of the knob, whereby one must know just what pin to push in and how to manipulate the pin and turn the knob before the lock can be unlocked.

Another object of the invention is to provide means for sounding an alarm when certain of the push pins are pushed in, thus indicating when an attempt is being made to unlock the device and the push pin can be deliberately manipulated to sound an alarm if one is being forced to unlock the device by a burglar or the like.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary elevation showing part of the door with the device forming the subject matter of this invention applied thereto.

Figure 2 is a view looking toward the inner face of the outer portion of the door and showing the parts in section and parts removed.

Figure 3 is a horizontal sectional view through Figure 1.

Figure 4 is a view of part of the rear face of the door showing the contact part and a circuit closing portion of the device.

Figure 5 is a view looking into the ring carrying casing with the closure plates removed.

Figure 6 is a view looking into the outer casing which carries the push pins.

Figure 7 is a plan view of one of the rings.

Figure 8 is a view of one of the closure plates of the inner casing.

Figure 9 is a sectional view through one of the rings and showing a clip in side view.

Figure 10 is a view of a push pin and its contact member.

Figure 11 is a view of one of the clips.

Figure 12 is a view of the spring actuated bolt control member.

Figure 13 is a fragmentary view of the tubular shaft with the projection thereon.

Figure 14 is a perspective of the plate with the projection thereon.

The drawings show the invention applied to the door of a safe but it will be understood that the invention can be applied to other types of barriers.

The door is shown at A and is shown as composed of the outer portion 1 and the inner portion 2, the two portions being separated and these portions are provided with holes for the passage of a tubular shaft or stem 3. An outer casing 4 is connected to the outer face of the door and an inner casing 5 is connected to the inner face of the outer part 1 of the door and the shaft passes through these casings and has a knob 6 connected to its outer end. The shaft has a sleeve 7 connected therewith which is located in the inner casing 5 and carries a projection 8 as shown more particularly in Figure 13.

A plurality of push pins 9 pass through radial holes in the casing 4 having their inner ends reduced and passing through holes in brackets 10 carried by the outer casing, springs 11 tending to hold the pins in their outermost positions. A disc 12 of non-conducting material is carried by the shaft 3, within the casing 4 and supports a metallic disc 12^X, Figures 3 and 6, secured on which is a plate 13 having a part 13' projecting from one end for engagement by the pins when the same are pushed inwardly. A contact ring 14 is carried by the disc 12 and is engaged by a contact member 15 attached to certain ones of the pins 9 when said pins are pushed inwardly. When the member 15 contacts the ring 14 a circuit is closed to an alarm, part of the circuit including the conductor 16 passing through the shaft 3 and connected with the ring 14 and also connected to a contact plate 17 connected to and insulated from the rear end of the shaft 3 as shown in Figure 3, a spring contact 18 contacting the plate 17 and this contact 18 is connected to the rest of the circuit which may be grounded on any suitable part of the device.

The foregoing will be better understood when it is stated that the projection 13' is for the purpose of stopping rotation. Upon pressing of any of the pins not in combination, the alarm is set off. Further, if the pin is pressed the metal disk has stopped or has been set, there will be an automatic contact and the alarm is set off. The contact member 15 shown attached to any of the pins not used as a combination member will serve

for the purpose of giving alarm upon being pressed.

A plurality of rings 19 are rotatably arranged in the inner casing 5 preferably by having enlarged edges engaging the grooves in the casing as shown in Figure 3, the rings being held in place by a plate 20 contacting the opposite edges of the rings and having spacers 21 thereon engaging a cover plate 22 which covers the inner end of the casing 5 and bears against the inner face of the door 1. Each ring 19 is provided with a slot 23 and each ring is also provided with spaced notches 24 of U-shape as shown more particularly in Figure 7, any one of these notches being adapted to receive a substantially U-shaped clip 25, shown in Figures 9 and 11. As shown in Figure 9 the sides of this clip extend beyond the sides of the ring so that one clip will engage a clip on an adjacent ring during the rotary movement of the rings and a clip carried by the inner ring will be engaged by the projection 8 of the sleeve connected to the shaft 3 when the shaft is rotated. Thus the inner ring is rotated from the shaft and communicates its movement to the next ring and the next ring will communicate its movement to the ring next to it and so on until all the rings are being rotated by the movement of the shaft 3 due to the turning of the knob 6. A substantially T-shaped member 26 is adapted to be pressed into the slots 23 of the rings when said slots are in alignment when said T-shaped member is pressed inwardly by a sliding member 27 having its beveled parts 28 engaging the beveled parts 29 of the T-shaped member when said sliding member is moved in a certain direction by the turning of a shaft 30 which is connected to said member 27 by a link 31, the shaft 30 being turned by a handle 32 and said shaft is journaled in the parts 1 and 2 of the door with the knob on the exterior of the door. The member 26 is normally held outwardly by a spring 33 on a stem 34 threaded in a hole 35 in the member 26, the spring being adjusted by a nut 36 threaded on the stem. The member 27 is of forked construction as shown in Figure 2 so that it will straddle the shaft 3 with the ends of the prongs bolted together and a spacer 38 on the bolt between the prongs. A guiding block 39 is fastened to the inner face of the part 2 of the door and located between the prongs and this member also limits the inward movement of the member 26. This member 27 is connected with the bolts of the door in any suitable manner and as it will be seen this member 27 cannot be moved by the shaft 30 or the shaft 30 rotated until the member 26 has moved into the slots 23 of the rings so that until the slots of the rings are in alignment the member 26 cannot move and thus this member prevents movement of the member 27 and of the shaft 30 so that the bolt cannot be retracted.

The pins 9 are provided with characters and each ring has the same number of slots 23 therein as there are pins and the slots are numbered the same as the pins, thus making it easy to change the combination and when the combination is to be changed it is simply necessary to place the clips 25 in those notches 24 bearing the same numbers or characters which are the new combination of the pins.

When the bolt or bolts of the door is in locking position and it is desired to open the door the knob 6 is turned to the right a certain number of times in order to move all the rings 19 in the same direction. Rotation is continued in this

direction but the pin 9 corresponding to the first number or character in the combination is depressed until the rotation is stopped by the projection 13' striking this pin or button. Then the knob is turned in the opposite direction and at the same time the second button of the combination is pressed. When rotation is stopped said second pin is momentarily released, allowing the rotation to continue and the button again depressed. Once again this is done on this button and at the third stopping of the rotation, the second part of the combination has been concluded. Rotation is now made in the original direction and the third button is pressed inwardly to stop the rotation and then the button is released and the rotation continues until stopped by said button. Rotation is now made to the left and the fourth and last button of the combination is depressed and when the first stop is made the lock is in open position, with slots 23 of the rings 19 in alignment. Then by turning the shaft 30 the member 27 will depress the member 26 into the slots and the bolt or bolts will be retracted and the door may be opened.

As before stated when an attempt is made to open the lock by one not knowing the combination the chances are he will push in one of the buttons carrying the contact member 15 so that the alarm will be sounded. These contact members should be placed on the buttons not used in the combination.

If one is forced to open the door by a bandit or the like the alarm may be made without disclosing the continuity of opening in the above manner. During the initial opening movement when the knob is turned to give all the rings their rotary motion, the operator can press any one of the buttons carrying the contacts to sound the alarm and after the few turns needed to set the rings all going the correct buttons can be pressed and the opening made as usual.

If it is feared that they could not press a wrong button at the start without being noticed, the alarm may be made at any time during the movements for the first three numbers without making any false movements or disturbing ease or speed of opening.

This is done in this manner: Suppose that one being forced to open the safe, is afraid to press the wrong button at the start. The operator would set up the correct number on the first part, and in the actual opening he would proceed to reverse the rotation, and press the second button and stop at this three times. Instead of that, he can press any button, stopping at it twice and for the third stop press the correct button. This may be done on any turn but the last making sure that you hold the wrong button one less stop.

In the event that a wrong button is used during the opening, it is impossible to open safe, and it is also impossible to rectify this but complete renewal of the opening process must be made.

It is thought from the foregoing description that the advantages and novel features of the invention will be readily apparent.

It is to be understood that changes may be made in the construction and in the combination and arrangement of the several parts provided that such changes fall within the scope of the appended claims.

What is claimed is:

1. A combination lock of the class described comprising supporting means, a shaft rotatably

arranged therein, an exterior knob connected with the shaft for rotating the same, a plurality of rings rotatably supported by the supporting means and each having a slot therein, said rings surrounding the shaft and each other, adjustable 5 projections on the rings, a projection on one ring engaging a projection on the other ring for communicating rotary movement of one ring to the adjacent ring, a projection on a sleeve on the shaft engaging the projection on the inner ring, 10 a second projection, a plate attached to the shaft, pins engaging the second projection when the pins are pushed inwardly and stopping rotary movement of the shaft, said pins having thereon combination characters, the slots in the rings being 15 aligned when the shaft has been rotated in a certain direction and stopped by certain of the pins and bolt controlling means manually operated and entering the aligned slots for retracting a bolt.

20 2. A combination lock comprising supporting means, a shaft rotatably supported thereby, a knob turning the shaft, a plurality of rings rotatably supported by said means, and each provided 25 with a slot, a projection on the shaft, adjustable projections carried by the rings, the projection of the inner ring being engaged by the projection on the sleeve on the shaft and the projections of the rings engaging each other in rotary movement 30 of the rings, a second projection carried by a plate attached to shaft, movable resiliently mounted pins for engaging the same when a pin

is pushed inwardly for stopping rotary movement of the shaft in a certain direction, a member adapted to enter the slots of the rings when the said slots are in alignment, a bolt controlling member, manually operated means for operating the same, said member moving the second member 5 into the slots when moved by the manually operated means.

3. A combination lock comprising a barrier, a casing connected with the outer face of the barrier, a second casing connected to the inner face thereof, a shaft passing through the casings, a handle on the outer end of the shaft, a plurality of rings rotatably arranged in the second casing, each having a slot therein, and spaced notches 15 therein, clips detachably engaging any one of the notches, said clips communicating the movement of one ring to another ring, a projection on a sleeve on the shaft engaging the clip on the inner ring for moving the same, a projection on the shaft located in the first casing, push buttons radially arranged in the first casing and when pushed inwardly engaging the projection carried 20 on the plate attached to the shaft to stop the rotary movement of the shaft, a member passing into the slots of the rings when the slots are in alignment, spring means for normally holding the member out of the slots, a slide moving said member into the slots when the slide is moved, and manually operated means for moving the slide. 30

JOSEPH SPADAFORA.
